UNITED STATES PATENT OFFICE.

SETH WHEELER, OF ALBANY, NEW YORK.

ASH-SIFTER.

Specification of Letters Patent No. 30,942, dated December 18, 1860.

To all whom it may concern:

Be it known that I, SETH WHEELER, of Albany, in the county of Albany and State of New York, have invented a new and useful Improvements in Ash-Sifters, the simplicity of construction and operation of which will be clearly set forth in the following specification.

The nature of my improvement consists 10 in the use of a reciprocating corrugated sieve, inclosed in a suitable case or box, and placed in a diagonal position, said sieve being hung on pivots or journals, and agitated by means of a lever or crank, rod and 15 treadle, by working on the outside of said case or box.

A scuttle provided with a pivot or journal on one side, and a square stud on the other, is suspended in the case or box, the 20 round journal working in a slot formed in one side, and a square stud resting in a socket which has a round shoulder, passes through the other side of said case or box and is provided with a handle or lever on 25 the outside. A cover fits closely over the top to prevent the dust from escaping while the machine is in operation, and two compartments or drawers are placed in the lower part and are divided by a deflecting 30 partition which extends up near the lower edge of the corrugated sieve, by means of which the sifted coal and cinders falls into one of the drawers and the ashes and dust into the other.

35 The operation of the machine is as follows: The cover of the case or box being removed the scuttle is taken out, filled and replaced within, resting on the slot cut in one side and the square socket in the other. 40 The cover is then put on and the handle secured to the square socket is turned, thereby dumping the scuttle and discharging the contents on the diagonal corrugated sieve, which is set in motion by a lever secured to its axis which is also connected to a treadle operated by the foot, by depressing which the corrugated sieve is raised, and 45 when the pressure is removed, a spiral spring connected to the rod and side of the 50 case or box, draws it back to its original position, thereby agitating the sieve and sifting the coal and ashes thoroughly.

Having thus set forth the nature of my improvement and to enable others skilled in 55 the art to make and use the same, I will now proceed to describe it and certify that the accompanying drawings are a full and

correct representation of the same like letters corresponding with like parts.

Figure 1 represents a longitudinal section 60 of the ash sifter; Fig. 2, a perspective view of the same with one side broken away to show the interior; Fig. 3, a side elevation of the same; Fig. 4, a transverse section of a part of the machine showing the scuttle 65 and manner of dumping.

A, Figs. 1, 2, 3, 4, is the case or box, B the diagonal corrugated sieve provided with bearings, b, b, to one of which is secured the lever C connected to the rod D passing 70 through a spiral spring E one end being secured to it and the other end being fixed to the case or box A.

F is a treadle secured to the lower end of the rod D which is kept in position by 75 the guide G.

H is a scuttle suspended on the stud (h) and square socket I (Fig. 4).

J is the handle fixed to it for dumping 80 the scuttle H.

K is a plate which covers the space between the upper end of sieve and side of box or case A and is secured to it for the purpose of preventing the ashes from falling through without sifting.

L is the cover of case or box A, M the deflecting plate or partition, N the drawer for the sifted coal, O the drawer for the ashes and dust.

The scuttle H when filled is placed in 90 the box A setting in the slot and the socket I (represented at Fig. 4). The handle J is then turned which dumps the scuttle H (as represented at Fig. 2) and discharges the contents on the plate K from which it falls 95 to the corrugated sieve B, which is then set in motion by means of the treadle F operating rod D and lever C. When the treadle F is depressed the sieve B is in the position indicated by dotted lines (Fig. 1) and when 100 the foot is removed the spring E draws it back to the original position, the coal and cinders fall into drawer N and the ashes and dust into drawer O.

I claim—

The use of lever C, treadle F and spring E when used in combination with the sieve B, substantially and for the purpose specified.

SETH WHEELER.
